CLAIM

I claim the ornamental design for a bird feeder, as shown and described.

DESCRIPTION

FIG. 1 is a front perspective view of a Bird Feeder showing our new design;

FIG. 2 is another front perspective view thereof;

FIG. 3 is a side perspective view thereof;

FIG. 4 is an elevational view thereof;

FIG. 5 is a top plan view thereof; and,

FIG. 6 is a bottom plan view thereof.

The broken line showing of a top cover is not claimed.
